UNITED STATES PATENT OFFICE.

NILS D. LEVIN, OF COLUMBUS, OHIO, ASSIGNOR TO THE JEFFREY MANUFACTURING COMPANY, OF COLUMBUS, OHIO, A CORPORATION OF OHIO.

CONVEYER.

1,358,167.

Specification of Letters Patent. Patented Nov. 9, 1920.

Application filed April 2, 1919. Serial No. 286,854.

To all whom it may concern:

Be it known that I, NILS D. LEVIN, a citizen of the United States, residing at Columbus, in the county of Franklin and State of Ohio, have invented certain new and useful Improvements in Conveyers, of which the following is a specification, reference being had therein to the accompanying drawing.

The present invention relates to certain new and useful improvements in conveyers, and particularly to that class of conveyers used for carrying coal away from a mine face and from positions in relatively low horizontal planes up to positions in relatively high planes.

The object is to construct such a conveyer with a single propelling chain, the trough and guideway having a horizontally disposed lower element at the receiving end and a horizontally disposed upper element at the discharge end, with an intermediate inclined or curved element, in combination with scraper elements having resilient connections with the propelling chain and adapted to travel along the horizontal and the intermediate elements of the trough and also adapted to avoid breakage or severe strains if they engage with obstructions such as large coal masses or the like.

The devices by which I attain this object are fully set forth in the following specification, reference being had to the accompanying drawings of which—

Figure 1 is a general plan view of a mining and loading machine which embraces my present invention.

Fig. 2 is a side elevation of the machine illustrated in Fig. 1.

Fig. 3 is a fragmentary longitudinal vertical sectional view taken along the line III—III of Fig. 4.

Fig. 4 is a transverse vertical sectional view taken along the line IV—IV of Figs. 1 and 2.

Fig. 5 is a fragmentary sectional view taken along the line V—V of Fig. 3.

Fig. 6 is a plan view of a fragment of the conveyer chain showing the method of attaching the conveyer flights.

Fig. 7 is a detail cross sectional view taken along the line VII—VII of Fig. 3.

Like numerals refer to similar parts in the several figures.

In my co-pending application Serial No.

184,946, filed August 7th, 1917, is disclosed a mining and loading machine adapted to dislodge coal from its native bed and to remove it rearwardly of the machine and load it into suitably positioned cars for transportation from the mine. The cutting apparatus of that machine produces a considerable quantity of fine coal which is discharged at points inaccessible to the principal loading conveyer, and an auxiliary conveyer is provided whereby this fine coal is reclaimed and deposited in the primary conveyer to be loaded by it into the pit cars. It has been found in practice that fragments of coal or other material too large to be successfully handled by this auxiliary conveyer occasionally get into the path of travel of the scraper flights, tending to jam the conveyer and subjecting the parts to destructive strains. The devices of this present invention have been provided to protect this conveyer from these excessive strains, with the consequent danger of breakage of the parts and interruption of the operation of the machine.

As shown in the drawings the mining and loading machine above referred to comprises an undercutting mechanism, indicated by the character "A," adapted to form a horizontal kerf at the base of the coal vein; two vertical shearing devices, "B" and "B," adapted to form vertical kerfs extending upwardly from either end of the horizontal kerf; breaking down mechanism, "C," adapted to engage the coal above the horizontal kerf and between the vertical kerfs to break it down; a receiving conveyer, "D," adapted at its forward end to enter the horizontal kerf with the cutting mechanism "A" to receive the coal as it is broken down, and transport it rearwardly of the machine; and a loading conveyer "E" adapted to receive the coal from the receiving conveyer and deliver it to a suitably positioned pit car "F" positioned upon the mine tracks at the rear of the machine. The cutting mechanism, breaking down devices, and the receiving conveyer are all mounted upon a suitable base frame 1 which is longitudinally slidable in a supporting pan 2 which rests directly upon the floor of the mine. Suitable feeding mechanism is provided for moving the base frame relative to the supporting pan to feed the cutting and break-

ing down elements to their work, and for moving the machine bodily over the floor of the mine to position it relative to the material which is to be mined.

5 The undercutting mechanism "A" is of the well known type comprising a guide frame 3 about the edge of which travels a cutter chain 4 having renewable cutter bits 5 by which the coal is cut. The cutter chain 10 passes around and is actuated by a sprocket wheel 6 (shown in Fig. 4) which is attached to the lower end of a vertical shaft 7 journaled in a suitable bearing 8 of the main frame casting 1. The shaft 7 carries at its 15 upper end a bevel gear 9 which engages the armature pinion 10 of the electric motor 11. The motor 11 is mounted upon the main frame 1, beneath the rearward portion of the receiving conveyer "D," and supplies 20 energy for the actuation of the various elements of the machine. As these elements form no part in the present invention further description of them is not thought to be required at this time. During the 25 operation of the machine the fine coal produced by the cutter bits 5 is carried rearwardly thereby and discharged upon the base pan 2 as the chain passes around the sprocket wheel 6. If these coal cuttings 30 were allowed to accumulate the machine would soon be completely choked and I have provided an auxiliary slack conveyer "G" (shown in longitudinal section in Fig. 3) to reclaim these cuttings, transport them 35 rearwardly of the machine, and deposit them in the hopper 12 of the loading conveyer "E."

The slack conveyer is indicated as an entirety by "G." It comprises a trough having a vertical wall and a bottom wall 23 at one side and a vertical wall and a bottom wall 24 on the other side, these walls being preferably formed of angle sheets (see Figs. 3 and 7). At their inner edges the angle 45 sheets are secured to the lower angle bars near the longitudinal central lines of the conveyer, upper angles being arranged above the lower ones. These angles form one or more box-like structures with slots 50 or openings between the edges of the angles.

The side walls of the trough and the angles are secured together in such way as to form a unitary structure which has a lower horizontally disposed element at the 55 receiving end and an upper horizontally disposed element at the discharge end, together with an intermediate inclined or curved element. The active element of this conveyer is an endless chain composed of welded links 60 13 formed of round steel rods, interspersed at spaced intervals with special attachment links 14 having laterally extending hinge members 15 to which the scraper flights 16 are attached. The chain being constructed 65 as above described of round rod welded

links, each lying in a plane at right angles to the planes of adjacent links, and being connected to the attachment links 14 in the way illustrated in the drawings, it will be seen that it (the chain) can be readily flexed 70 horizontally or vertically along its length. It travels smoothly along the lower and the upper elements of the trough and also along the intermediate inclined element. And at any point the flexibly attached flights are 75 allowed to move relatively to the chain as described. This chain passes around a drive sprocket wheel 17 mounted underneath the rear end of the main conveyer for rotation about a vertical stud 18 which is integral 80 with the casting 19 secured to the main frame 1 by means of bolts 20, and to each casting the parts of the upper element of the trough are secured. At the forward end of the conveyer the chain passes around 85 an idler sprocket wheel 21 which is mounted in a bracket 22 in such position that the flights 16 may engage the coal cuttings upon the pan 2 near the point where they are dropped by the cutter bits 5 of the cutter 90 chain. The flights 16 push the cuttings onto and along the lower part of the conveyer trough and then of the inclined part and finally discharge them into the hopper 12 of the loading conveyer "E" which receives the larger coal masses from the receiving conveyer "D." The bottom wall of the sheet angle 24 supports the return strand of the conveyer element. A bevel gear 25 is attached to the sprocket wheel 17 and engages a bevel gear 26 mounted upon the longitudinal power shaft 27 to drive the conveyer. The power shaft 27 is connected through suitable gearing with the motor 11 but as these devices form no part in the 105 present invention further description of them at this time is not thought to be required. The idler sprocket wheel 21 is journaled on a stud 28 of the casting 22 and is held in place by the guard member 29. The casting 22 is supported for limited movement longitudinally of the machine by an extension 30 which engages a suitable guide way 31 formed in the main frame casting 1. The position of the casting 22 is controlled by the adjusting screw 32 and the nut 33 manipulation of which produces the adjustment necessary to properly tension the conveyer chain.

The scraper flights 16 are pivotally connected to the hinge members 15 by suitable hinge pins 34. Springs 35 are provided to rotate the scraper elements forwardly about the hinge pins 34, and shoulder extensions 36 on the hinge members 15 engage the forward surfaces of said flight to limit their forward rotation. By this arrangement the flights are held in position to move the fine coal cuttings along the conveyer trough, while the resiliency of the springs 35 allows 120 125 130

the flights to yield to excessive pressure and prevents breakage of the parts should they encounter fragments of coal or other objects too large to pass through the conveyer 5 trough.

What I claim is—

1. In a conveyer, the combination of a trough having a horizontally disposed relatively low receiving end; a horizontally disposed relatively high discharge end, and an intermediate inclined part between the said receiving and discharge ends, and a chain 10 flexible in vertical and horizontal planes adapted to longitudinal movement parallel with said trough, and having flights resiliently attached thereto and held with their axes fixed in vertical planes.
2. In a conveyer, the combination of a trough having a horizontally disposed relatively low receiving end; a horizontally disposed relatively high discharge end, and an intermediate inclined part between the said receiving and discharge ends, a universally 15 flexible chain adapted to longitudinal movement parallel with said trough and having hinge attachments secured thereto; flights hinged to said attachments and held with their axes fixed in vertical planes, and resilient means to hold said flights in position 20 to propel material along said trough or to permit said scrapers to be deflected around relatively immovable obstacles.
3. In a conveyer, the combination of a 25

trough having a horizontally disposed relatively low receiving end; a horizontally disposed relatively high discharge end, and an intermediate inclined part between the said receiving and discharge ends, a universally 30 flexible chain adapted to longitudinal movement parallel with said trough and having flights hinged thereto, said flights being held with their axes fixed in vertical planes during the travel along said trough, and resilient means to hold said flights in position to propel material along said trough. 35

4. In a conveyer, the combination of a trough having a horizontally disposed relatively low receiving end, a horizontally disposed relatively high discharge end, and an intermediate inclined part between the said 40 receiving and discharge ends, a chain universally flexible and adapted to travel along and be held adjacent to the bottom of said trough from end to end thereof, flights hinged to said chain and held with their 45 axes fixed in vertical planes during their travel along said trough, and resilient means to hold said flights in position to propel material along said trough.

In testimony whereof, I affix my signature, in presence of two witnesses.

NILS D. LEVIN.
